FREDERICK W. CHRISWELL, OF SEATTLE, WASHINGTON, ASSIGNOR TO PACIFIC CAR AND FOUNDRY COMPANY, OF SEATTLE, WASHINGTON.

BODY-BOLSTER CONSTRUCTION.

Application filed January 19, 1926. Serial No. 82,223.

My invention relates to a body bolster construction constituting part of a car under-frame, particularly designed for use in logging and other cars where a rugged support 5 is required for a bunk or similar transverse load supporting member.

The invention comprises an improvement in known forms of bolster construction where the body bolster proper is centered on a truck, 10 supports a center sill, and the opposite sides of which engage bolster brackets which form cantilever extensions from opposite ends of the body bolster. In such known constructions the center sills which usually are, or contain, 15 wooden beams, are secured to the outstanding brackets. The position of these brackets relative to both the supporting bolster and to the supported bunk, are thus necessarily controlled by the width of the center sill. As these wooden center sills vary in 20 width, it is not possible to provide for a standard form of bolster to fit any of the usual characters of center sill.

Accordingly the primary object of the 25 invention is to provide a simple form of fabricated bracket form of bolster structure which can be formed as a standardized unit, capable of receiving center sills of variable width and of various types, and which at the same time 30 will provide a rugged construction for transmitting strains from the bunk or similar load carrying member directly to the bolster and without necessity of utilizing the center sill as a part of the strain transmitting means.

Broadly I attain this object by providing a 35 bolster assembly for logging cars which includes a fabricated bolster of the type having outstanding cantilever brackets, but which distinguishes from known similar structures 40 in that there is no necessary connection between the brackets and the center sill. Differently expressed, the invention features a fabricated bolster which will provide a support for different types of center sills but 45 which will be otherwise independent of the center sills.

Another object of the invention is to provide, in a structure of the type outlined, a 50 form of bolster bracket designed to give maximum strength in those portions where distorting strains are most likely to develop and at the same time to form a bracket which will be light in weight; which may be conveniently formed of a single casting and which will fea-

ture an economic disposition of the metal 55 used to brace the casting against bending or breakage.

An incidental object of the invention is to provide a bolster bracket reinforced as usual by integral webs or flanges, but in which 60 these webs or flanges are disposed and arranged to perform functions other than reinforcing features, such as to provide elements of bearings, connectors for tie rods, seats for side sills, and the like. 65

A further object of the invention is the provision of a bolster bracket so formed as to provide a seat for receiving and supporting a side sill and also to provide supporting means for truss rods or the like for retaining the 70 sills against displacement.

Various other objects and advantages of the invention will be apparent from an inspection of the accompanying drawings and in part will be more fully set forth in the 75 following particular description of one form of mechanism embodying my invention, and the invention also consists in certain new and novel features of construction and combination of parts hereinafter set forth and 80 claimed.

In the accompanying drawings:—

Figure 1 is a view in elevation of a bolster and bracket parts constructed in accordance with my invention, certain parts being shown 85 in section.

Fig. 2 is a fragmentary top plan view of the bolster assembly, certain parts being shown in broken lines, the view also showing fragmentary portions of the center beams. 90

Fig. 3 is an end elevation of the bolster member, certain parts that are associated therewith being shown by broken lines, and,

Fig. 4 is a detail section, showing a portion 95 of the bracket, a portion of the body bolster and a portion of one of the center beams showing the arrangement of the several parts.

In the following description and in the claims parts will be identified by specific 100 names for convenience of expression but they are intended to be as generic in their application to similar parts as the art will permit.

The drawings disclose a bolster assembly for a car of the type hereinbefore mentioned 105 which comprises a body bolster 10 journalled as indicated at 11 in the truck bolster 12 and in other respects corresponding to the usual

structure of these parts. The top 13 of the bolster 10 is designed to support a center sill 16 which in the instance shown is of conventional construction. Obviously the top 5 of the bolster may be flat or it may be designed to receive some particular form of center sill. In the form of the invention herein selected for illustration the center sill is of a three beam type and comprises a central wooden beam 17 and outer wooden beams 18 and 19. The center sill construction also includes I-beams 20 and 21 positioned between the center beam 17 and the outer beams 18 and 19 and resting on the body bolster 10. 15 Positioned at opposite ends of the bolster are brackets 23 and 24 which coact to form cantilever extensions from opposite ends of the bolster.

The brackets are identical in form, hence 20 a description of one will suffice for both, and now referring to the brackets in detail, each comprises a top plate 26 having an opening 43 formed therein arranged adjacent the inner end thereof. The top plate is provided with a depending flange or web indicated generally at 27 which extends substantially from end to end of the plate and is arranged midway between the sides thereof. At the rear or inner end of the bracket, the flange 27 is 25 formed into an end plate 50 which is arranged at substantially right angles to the rear end of the flange 27, and in the positioning of the bracket on the body bolster, the flange or end plate 50 is normally spaced from the beam 18 as clearly shown in Fig. 4. The bracket is 30 also provided with a supporting base 30 which extends at substantially right angles to the flange 27 and is arranged parallel to the top plate 26; the supporting base 30 serving to mount the bracket on the end portion of the body bolster 10, as clearly shown in Figs. 1 and 4. Adjacent the forward edge of the 35 base plate 30, a shoulder 25 is formed which, when the bracket is positioned on the body bolster 10, engages the end of the body bolster 10 to position the bracket on the body bolster with the end plate 50 in spaced relation as heretofore mentioned. The flange 27 as before-mentioned extends 40 to the outer end of the top plate 26 and is provided with spaced perforated bosses 37 and 38 through which the ends of truss rods 39 extend to be secured by nuts 39' (see Fig. 3). The truss rods serve to prevent displacement of the side sills 36 which 45 are positioned on and supported by a bottom plate 52, the latter being provided with depending inverted T-shaped elements 33 which form the upper member of an outside bearing, as will be apparent from Figs. 1 and 3. The bottom plate 52 and the outside bearing members 33 are reinforced by webs 32 (see Fig. 1). From the description just given, it 50 will be apparent that the side sill 36 may be slipped into the space between the top plate

26 and the bottom plate 52 to be supported therein and the same is retained against outward shifting by the truss rods 39. As shown in Fig. 3, a web 54 is provided which extends between and is preferably formed integral with the top plate 26, the flange 27 and the bottom plate 52, to define a recess 35 for receiving the end of the sill 36; the web positioning the sill and the before-mentioned truss rods preventing displacement thereof. 70

The flange 27, as shown in Fig. 1, inclines upwardly from the rear end of the bracket toward the outer end, and a portion thereof is cut away to define an opening 44 which is arranged beneath the opening 43 heretofore so mentioned. For reinforcing purposes as well as for permitting the egress of chips or the like from the bunk hereinafter mentioned, the edge of the flange about said opening 44 is provided with a flange or web 28 which is 85 of gradually increasing width toward the rear of the bracket, as shown clearly in Fig. 2, the flange 28 terminating in a vertical flange 29 arranged adjacent the inner end of the opening 44, and of course, positioned at substantially right angles to the portion 56 of the flange 27, the flange 29 serving to brace the bracket and being arranged substantially parallel to the end plate 50 of the bracket. The flange 27 is further provided with reinforcing 90 ribs 58' arranged in the angle formed by the base 30 and the flange 27 as clearly shown in Fig. 1. For securing the bracket to the body bolster, bolts 31 are provided which extend through the base 30 and body bolster 10. 100

It will be apparent from the above description that the tops or upper surfaces of the brackets form transversely spaced apart wide flat surfaces for receiving and supporting a bunk 40 or other load supporting member. The lower surface of each end of the bolster 10 is flattened, as shown in Fig. 1, to provide an upper element 34 of an inside bearing, the bearing elements 33 and 34 being adapted and so arranged as to cooperate with lower bearing elements 58 and 60 respectively on the truck bolster 12. 105

Where it is desired to support the bunk at its mid-length, the top of the center sills may be formed flat and leveled with the top of the brackets to provide a center support. 110

In operation it will be understood that the bolster structure herein disclosed is fabricated by assembling the bolster proper and securing the brackets in position as illustrated. The unit thus constructed is positioned on the truck bolster following conventional practice, after which the center sills are positioned and secured directly to the bolster in the space between the outstanding brackets. 115 The center sill may be secured directly to the bolster proper by bolts 41 inserted through suitable bolt holes formed in the center portion of the bolster. The side sills which have had their ends fashioned to fit in the recesses 120

in the brackets are disposed in position and secured to the seat, if desired. The ends of the side sills abut against the flange 27 and in this way the side sills act as spacing means for the bolster assemblies at opposite ends of the car underframe. The load supporting member or bunk is positioned on the top plates and fixed thereto to extend across the center sills. The bunk may be secured at opposite ends by bolts passed through the bolt holes 42 formed in the top plates of the brackets and the parts may otherwise be secured following conventional practice. The bunk may be secured to the center sills, if desired, and in this way there is provided a support for the bunk continuous from end to end.

By means of a bolster construction of the type disclosed it is possible to design a cantilever form of bolster in which the brackets 20 may be accurately located on the main bolster, and secured thereto in that preset position best suited to receive and transmit those shocks and strains which it is intended to receive and at the same time to accommodate between the brackets any of the usual size and form of center sills. This disclosure further features an economical disposition of the metal used to obtain strength with lightness in weight and the formation of an all-steel bolster structure which will coat with the wooden sills and other associated underframe structures to provide a rugged and easily manufactured car structure.

The entire assemblage shown herein, including the truck bolster and the body bolster assembly, provides an arrangement of parts in which strains or stresses to which it may be subjected are taken up and equally distributed by means of the several bearings shown clearly in Fig. 1; the bearings including inner and outer side bearings together with the center bearings, and it will be apparent that any weight on the bolster assembly is evenly distributed due to the specific arrangement of parts.

To remove the side sill 36, in the event that it is necessary to do so, release the tension on the tie rods 39 and remove the same and then slide the sill sidewise through the open end 50 of the webbed recess 35. It will be obvious that a new sill can be replaced without very much labor or expense.

While I have shown and described, and have pointed out in the annexed claims, certain novel features of my invention, it will be understood that various omissions, substitutions and changes in the form and details of the device illustrated and in its operation may be made by those skilled in the art without departing from the spirit of the invention.

What I claim is:

1. In a car underframe, the combination of a car body bolster, a center sill supported centrally thereon, brackets carried at opposite ends of the bolster, a bunk supported on

the center sill and brackets, said brackets being in spaced relation to, and independent of, the center sill and said center sill substantially filling the space between the brackets and coacting with the brackets to provide a substantially continuous support for the bunk.

2. In a car underframe, the combination of a body bolster provided on the underside of its outer end with an element of an inside bearing and the upper surface of which is provided at one end with a seat affording a stop shoulder, a bolster bracket having its inner portion engaging said seat, and abutting said shoulder to prevent inward movement, means for securing the bracket to the bolster, and said bracket extending beyond the bolster and provided with a depending portion forming an element of an outside bearing in spaced relation to the inside bearing element provided by the bracket.

3. In a car underframe, a body bolster construction including a central member and outstanding brackets supported at opposite ends of the central member and constituting cantilever extensions projecting beyond the ends thereof, means for securing the brackets to the central member, said brackets being spaced apart to provide a space therebetween for accommodating a center sill, a center sill supported directly on the central member, and having a width slightly less than the distance between the brackets and a bunk supported at its outer ends on the outer ends of the brackets.

4. In a car underframe, a body bolster having a wide horizontal central portion reducing outwardly in width to a relatively narrow end portion providing a bracket seat, a bracket including a relatively wide top plate and a depending web supported on the narrow end portion of the bolster and means for securing the bracket to the bolster.

5. In a car underframe, an all-steel bolster construction complete per se and independent of any sill structure, said bolster construction being a fabricated unit and comprising a central member, a pair of brackets supported at opposite ends of the central member and providing cantilever extensions therefrom, fastening means securing the brackets to the central member, said brackets being spaced apart to provide a space for accommodating therein a center sill and the top of said center member facing said space constituting a seat for receiving the center sill and said center member provided with bolt holes adapted to receive bolts for fastening the center sill directly to the center member.

6. In a car body bolster, the combination of a body bolster, a bracket secured to the outer end of the bolster and constituting a cantilever extension therefrom, said bracket including a top plate, a web depending centrally of the plate and transversely extend-

ing webs for bracing the plate laterally and a horizontally extending bottom web coacting to form a seat for receiving a side sill.

7. In a car body bolster, the combination 5 of a body bolster, a bracket secured to the outer end of the bolster and constituting a cantilever extension therefrom, said bracket including a top plate, a web depending centrally and longitudinally from the underside 10 of the plate and transversely extending webs for bracing the plate laterally, the lower end of one of said transverse webs constituting the upper element of an outside bearing.

8. In a car body bolster, the combination 15 of a body bolster, a bracket secured to the outer end of the bolster and constituting a cantilever extension therefrom, said bracket including a top plate, a web depending centrally and longitudinally from the underside 20 of the plate and transversely extending webs for bracing the plate laterally and said longitudinal web provided with an opening for receiving a tie rod.

9. In a car underframe, the combination 25 of a body bolster, a one-piece bracket secured to the outer end of the bolster, said bracket provided with a seat for receiving a side sill and provided with an upper element of an outside bearing positioned directly below the 30 seat.

10. In a car underframe, a bolster bracket provided with a vertically disposed web-plate having webs extending laterally from opposite sides thereof, certain of said webs 35 forming a side-sill receiving seat on one side thereof and another of said webs forming a bearing element said web-plate constituting an abutment for the end of the side sill.

11. In a car frame, a bolster bracket provided with a top plate, a web plate increasing 40 in depth from a point intermediate its ends towards one end, said end of increased depth depending therefrom, said plate provided with horizontal enlargements extending 45 laterally from opposite sides thereof and forming a wide spreading bottom adapted to be seated on a bolster.

12. In a car frame, a bolster bracket provided with a top plate, a web plate depending 50 therefrom, the inner end of said plate provided with lateral enlargements forming a wide spreading bottom of less length than the top plate and adapted to be seated on a bolster with the outer end of the bracket projecting beyond the bolster, said wide spreading bottom being provided with flanges for securing the inner ends of the bracket to the outer end of the bolster.

13. In a car underframe, a bolster bracket 60 provided with a long rectangular top plate, a web plate depending integrally and longitudinally therefrom, the underside of said web plate being recessed to provide space to accommodate part of the truck frame above the bottom of the bracket, and said web plate

provided with a tie-rod receiving opening, and means integral with the web plate for reinforcing the recessed part of the same adjacent the opening.

14. An all metal bolster construction including a central member, a bracket constituting a cantilever extension from one end thereof, the outer end of said bracket depending below the top of the central member to form an element of an outside bearing, means for 70 locating the bracket on the central member with said element spaced outwardly from the same and means for securing the bracket in its located position.

15. A bolster construction including a body bolster provided with an element of an inside bearing, a bracket constituting a cantilever extension from the bolster, means for securing the bracket to the bolster, said bracket including a depending portion at its 75 outer end in spaced relation to the inner bearing and constituting an element of an outer bearing.

16. A bolster bracket in the form of a single casting comprising a top plate, a longitudinally extending web plate depending therefrom and recessed on its underside to form an inner and on outer portion and reinforcing elements extending integrally and laterally from both portions of the web plate, means 80 for securing the bracket through one of said reinforcing elements on the inner portion to a bolster and one of the reinforcing elements on the outer portion and beneath the top plate 85 constituting a means for receiving a longitudinal element of a car underframe construction. 90

17. A bolster construction comprising a body bolster having a wide center portion constituting a center sill seat, and an end portion constituting a bracket seat and projecting beyond the bolster end, a bracket having a relatively narrow bottom portion resting on the narrow bracket seat and having a top plate substantially as wide as the center 105 portion of the body bolster. 110

18. In a car of the kind described, a bolster assembly comprising a bottom member, cantilever extensions secured to said member and each provided with a side bearing portion at 115 its end, side sill positioning means formed with the extensions, and perforated bosses formed integral with said extensions and adapted to receive and support truss rods at each side of a side sill to prevent displacement of the latter.

19. A bolster assembly comprising a bottom member having a side bearing portion at each end thereof, a bracket section secured to each end of the bottom member and provided with a side bearing portion at its end spaced from the before-mentioned side bearing portion, said bracket sections each having an opening through the upper surface thereof and being provided with a web having an 120 125 130

opening therethrough in coincidence with the before-mentioned opening, side sill positioning flanges formed with the bracket sections, and perforated bosses formed with the bracket sections and adapted to receive and support truss rods at each side of a side sill.

25

20. The combination with a truck bolster having spaced side bearing portions near its ends, of a body bolster secured thereto and
10 provided with side bearing portions near its ends cooperating with certain of the side bearing portions on the truck bolster, cantilever extensions connected with said body bolster and each having a side bearing portion
15 spaced from the body bolster and so arranged as to cooperate with the other truck bolster side bearing portions.

21. In combination, a truck bolster, a body bolster secured thereto, cantilever extensions
20 connected with the body bolster, spaced side bearing portions at each end of the truck bolster, and side bearing portions at the ends of the body bolster and at the end of each

cantilever extension registering with the side bearing portions of the truck bolster.

25

22. In combination, a truck bolster having spaced side bearing portions near each end thereof, a body bolster secured to the truck bolster, bracket sections rigidly secured to the body bolster and each provided with an opening through the upper portion thereof, said bracket sections including a web provided with an aperture in coincidence with the before-mentioned opening, and side bearing portions formed with the body bolster and bracket sections for cooperation with the side bearing portions of the truck bolster.

30

23. A bolster assembly comprising a body bolster having side bearing portions near each end thereof, cantilever extensions secured to the body bolster and provided with openings therethrough, and a side bearing portion formed with each extension.

35

In witness whereof, I hereunto subscribe my name this 4th day of January, A. D. 1926.

FREDERICK W. CHRISWELL.
